ENGINE STARTER

John B. Dyer, Pendleton, Ind., assignor to General Motors Corporation, Detroit, Mich., a corporation of Delaware

Application August 19, 1935, Serial No. 36,866
Renewed September 19, 1936

31 Claims. (Cl. 74—7)

This invention relates to apparatus for starting internal combustion engines.

The objects of the invention are chiefly to provide an engine starter which is efficient, durable and quiet in operation and which is economical to construct. According to the disclosed embodiment of my invention these objects are accomplished by providing friction drive between the engine to be started and the starting motor, said drive comprising a disc or annular flange associated with the engine fly-wheel or other member connected with the engine crank shaft and a pair of driving discs which are driven by the starting motor and which are engageable with opposite faces of the driven disc. My invention includes means operating independent of the motor for causing the driving discs to move into engagement with the driven disc before the motor operates and means which responds to the operation of the motor for causing the driving discs to be pressed against the driven disc with a pressure sufficient for driving engagement between the starting motor and the engine, said pressure being released when the engine becomes self operating so that the engine may run free of the starting motor and the motor will not be driven by the engine. As will be more apparent hereinafter, the shock or abnormal strain attendant upon establishment of connections between the starting motor and the engine has been minimized, and, consequently, the operation of the starter drive mechanism has been made more quiet, so that the durability as well as reliability of the starter drive mechanism has been greatly improved.

Further objects and advantages of the present invention will be apparent from the following description, reference being had to the accompanying drawings wherein a preferred embodiment of one form of the present invention is clearly shown.

In the drawings:

Fig. 1 is a side view partly in section showing a preferred embodiment of the invention in its normal condition.

Fig. 2 is a fragmentary longitudinal sectional view of a starting apparatus.

Fig. 3 is a wiring diagram thereof.

Figs. 4 and 5 are fragmentary views similar to Fig. 1 showing the apparatus in two positions prior to rendering the starting motor operative.

Fig. 6 is a fragmentary view partly in section, this view being taken in the direction of the arrow 6 of Fig. 5.

Fig. 7 is a sectional view on the line 7—7 of Fig. 4.

Fig. 8 is a fragmentary sectional view on the line 8—8 of Fig. 5.

Figs. 9, 10 and 11 are diagrammatic views corresponding respectively to Figs. 1, 4 and 5.

5 The motor 20 for starting the internal combustion engine is preferably an electric motor comprising field frame 21 associated with an end frame 22 and a housing 23 which carry bearings 24 and 25, respectively, for the motor armature 26 which carries an armature 27.

Referring now particularly to Figs. 1 and 2 the shaft 26 carries a sleeve 30 which is splined at 31 to the shaft 26 so that the sleeve 30 is at all times drivingly connected with the shaft 26 but may 15 slide thereon to a limited extent. The left hand end of the sleeve 30 shown more particularly in Fig. 6 is provided with diametrically opposite longitudinally extending notches 32, which receive respectively tongues or lugs 33 which extend inwardly from the hub of a yoke member 34 which is mounted upon the sleeve 30. The yoke 34 is provided with arms 35 which are apertured to receive bearing pins 36 which are diametrically aligned with respect to the sleeve 30 and which extend 20 into diametrically opposite holes 37 provided by the sleeve 30. Each of the pins 36 carries a roller 38 serving as a cam follower for a purpose to be described. The yoke 34 is secured in position as shown in Fig. 2 by nut 39 cooperating with the 25 threaded left end 40 of the sleeve 30. A locking washer 41 is located between the nut 39 and the hub of the yoke 34. Thus the yoke 34 is drivingly connected with the sleeve 30 through the lugs 33 of the yoke 34 and through the pins 36. The 30 sleeve 30 is urged against the end of the bearing 25 by spring 42 which surrounds the armature shaft 26 and which is located between the armature 27 and the threaded end 40 of the sleeve 30.

The sleeve 30 supports a second sleeve 50 which 35 carries on its exterior a multiple screw thread of long lead comprising helical threads 51 which are shown in cross-sectional view in Fig. 7. The helical threads 51 cooperate with a nut which is provided by the inwardly extending annular flange 40 52 of a collar 53 having an outwardly extending flange 54. The sleeve 50 is provided with two shoulder portions. The right hand shoulder portion is provided by a spring ring 55 which is snapped into an interrupted groove cut into the 45 threads 51 near the right hand end thereof. The left hand stop is provided by a ring 56 secured to the sleeve 50. A helical spring 57 surrounds sleeve 50 and is located between ring 56 and flange 52 of sleeve 50. Spring 57 urges the sleeve 53 until 50 it engages the stop 55. Sleeve 50 is provided with

a pair of cams which respectively cooperate with the pair of rollers 38. Each of these cams include a surface 60 of greater pitch and a surface 61 of lesser pitch. As shown best in Fig. 9 the surface 60 of each of these cams is separated from the surface 61 of the other of these cams by a projection 62 which limits movement of a roller 38 in one direction relative to the cam 60.

The function of the sleeve 53 is to receive a longitudinal sliding movement and to effect rotary movement of the sleeve 51. In order to prevent rotation of the sleeve 53 while it is imparting the rotary movement of the sleeve 50, sleeve 53 is provided with a pair of diametrically opposite lugs 64 adapted to engage the sides of the yoke arms 35 the point of engagement being indicated at 64X in Fig. 6. The longitudinal sliding movement of the sleeve 53 is effected by means which operates independently of the starting motor. This means comprises a shifting lever 70 having at its upper end an elongated hole or slot 71 which receives a pin 72 carried by bifurcated bracket 73 integral with a Z-shaped bracket 74 attached to an electromagnet frame 75 mounted upon the motor frame 21. A spring 76 surrounds a stud 77 attached to the bracket 73 and urges the upper end of the lever 70 against the pin 72. The lower end of the lever 70 is bifurcated in construction so as to provide two arms 78 each carrying a pin or stud 79 for engaging the annular flange 54 of the collar 53.

The lever 70 is actuated electromagnetically by means which will now be described with reference to Fig. 3. The electromagnet frame 75 is preferably carried by the motor field frame 21. As shown diagrammatically in Fig. 3, magnet frame 75 encloses electromagnet windings 80 and 81 surrounding a movable solenoid armature 82 guided by the magnet frame 75 for a sliding movement toward a stationary core 83 which is located in the magnetic flux circuit of the electromagnet. The armature 82 is connected by a link 84 with the lever 70. Armature 82 is associated with a rod 85 upon which is mounted a non-conducting collar 86 yielding urged by spring 87 against a shoulder 88, the spring 87 being confined between the collar 86 and a washer 89 held from moving toward the right by a pin 90. A spring 91 located between a stationary part 92 and the rod 85 normally maintains the rod 85 and the armature 82 in the normal position as shown in Fig. 3.

The collar 86 carries a movable switch contact 95 adapted to engage with contacts 96 and 97 of the starting motor switch. Contact 96 is connected by wire 98 at a switch terminal 99. Contact 97 is connected with the starting motor 20 which is grounded at 100. Terminal 99 is connected with storage battery 101 grounded at 102. Terminal 99 may be connected simultaneously with terminals 103 and 104 by a movable contact 105. Terminal 104 is connected with contact 106 of an automatic switch having also a terminal 107 connected with windings 80 and 81, 81 being connected with contact 97 and 80 being grounded at 108. This automatic switch, designated in its entirety by numeral 110, comprises a suction chamber 111 connected by pipe 112 with the intake manifold of an internal combustion engine. One wall of the chamber 111 is provided by a diaphragm 113 which is attached to switch contact 114, said contact being normally in engagement with contacts 106 and 107, said engagement being effected through the action of a

spring 115 located so as to press the diaphragm 113 downwardly as viewed in Fig. 3.

The driving connection between the armature shaft 26 and the engine is effected by a pair of drive discs which are adapted to engage with opposite sides of a driven disc provided by the engine. This driven disc may take the form of an annular flange 120 extending from the periphery of the engine fly-wheel 121 which is indicated in Fig. 8. The disc which engages the right hand face of the driven flange 120 is provided by the shoulder 122 of the sleeve 30. The driving disc which engages the left hand side of the driven disc 120 is provided with the shoulder 123 of the sleeve 50.

As stated before, this invention embraces the feature of causing the driving discs 122 and 123 to be moved into engagement with the driven disc 120 before operating the starting motor 20. This is accomplished by means independent of the motor, namely, the electromagnet means shown diagrammatically in Fig. 3. The manner in which the driving discs are caused to engage the driven discs will now be described particularly with respect to Figs. 9, 10 and 11.

To start the engine the operator turns the switch contact 105 so as to cause it to engage the contact 103 and the contact 104. The ignition is then turned on, the ignition circuit being connected with the terminal 103 which is then connected with the battery 101. The terminal 104 then being also connected with battery 101, current will flow from the battery 101 through the windings 80 and 81, the former being directly grounded at 108 and the latter being indirectly grounded through the motor 20. The electromagnet windings 80 and 81 being energized, the armature 82 will move toward the left thereby causing the lever 70 to move to swing toward the left in a clock-wise direction around its pivot 72. During the movement of the lever 70 the contact 95 will be moving toward contacts 96 and 97 but before engagement of these contacts actually occurs the driving discs 122 and 123 will be brought into engagement with the driven disc 120 in a manner which will be apparent from a consideration of Figs. 9, 10 and 11. As lever 70 swings toward the left carrying with it the studs 79, the sleeve 53 will be moved first from the position shown in Figs. 1 and 2 to that shown in Fig. 4 and the sleeve flange 52 will be moved from the position shown in Fig. 9 to that shown in Fig. 10. For purpose of illustrating the movement which takes place, one of the short, wide helical threads provided by the flange 52 is shown in section 52X in Figs. 9, 10 and 11. As the thread 52X moves toward the left it is prevented from rotating in the direction in which it would tend to rotate when in engagement with threads 51 of sleeve 50 due to the fact that extensions 64 of collar 53 engage at 64X with yoke arms 35 as shown in Fig. 6. Therefore, owing to the mass of the shaft 26 and the parts rotatable therewith, the inertia against rotation causes the shaft 26 to remain stationary during movement of the collar flange 52 toward the left from the normal position shown in Fig. 9. Therefore, the flange thread 52X moves longitudinally toward the left but does not rotate after the projection 64 has engaged the yoke arm 35. Therefore, longitudinal movement of the collar flange 52 toward the left causes the sleeve 50 to rotate in a counter-clock-wise direction as viewed in the direction of the arrow 50X in Fig. 9. Since the rollers 38 tend to

remain stationary due to the inertia of the armature shaft and parts associated therein, this counter-clockwise rotation of the sleeve 50 causes the sleeve to be moved toward the right along sleeve 30 due to the camming action between camming surfaces 60 and 61 and rollers 38. This results first in the engagement between the driving disc 123 and the left hand face of the driven disc 120 as shown in Fig. 10. This movement has been effected due to the cooperation between the rollers 38 and the cams 60 of greater pitch.

Continued movement of the lever 70 toward the left, before the motor switch closes, causes the roller flange 52 to be moved from the position shown in Fig. 10 to that shown in Fig. 11, thereby causing further rotation of the sleeve 50 in a counter-clockwise direction as viewed in the direction of the arrow 50X. Since the driving disc 123 of sleeve 50 has already engaged the driven disc 120, sleeve 50 cannot move any further toward the right. Hence the cam 61 cooperates with the roller 38 in a manner such as to cause the sleeve 30 to move toward the left against the action of the spring 42. In doing so the driving disc 122 of the sleeve 30 is caused to move toward the left from the position shown in Fig. 10 to that shown in Fig. 11 until it engages the driven disc 120. After this occurs the lower end of the lever 70 cannot move any further toward the left.

Continued motion of the solenoid armature 82 toward the left to close contacts 95, 96 and 97 may take place by reason of the fact that there is lost motion between the upper end of the lever 70 and the pivot bearing 72. Just before these contacts are closed, the spring 76 is held by the solenoid armature 82 under compression, so that yielding pressure is applied between rollers 79 and collar flange 54. Therefore, it is only after the driving discs have been brought into engagement with the driven discs under yielding pressure that the motor switch contact 95 is caused to engage the stationary contacts 96 and 97. When this occurs the motor 20 operates to turn the shaft 26. The winding 81 is then short circuited and winding 80 only is effective to hold the motor switch closed. Winding 80 comprises preferably a large number of turns of fine wire and winding 81 fewer turns of coarser wire. Both windings are necessary to attract the armature 82 initially toward the core 83 but winding 80 only is required to maintain the armature 82 in its attracted position. The starting motor then will operate to cause the shaft 26 to rotate in a clockwise direction as viewed looking in the direction of arrow 50X of Fig. 9. At the instant the motor starts to turn the shaft 26, the driving discs 122 and 123 being then in engagement with the driven disc 120 and the driving disc 122 being directly splined to the shaft 26 the driving disc 122 tends to run ahead of the driving disc 123 and the roller 38 tends to run ahead of the cam 61 as viewed in Fig. 11. This tendency of the roller 38 to run up along the cam 61 tends to wedge the driving disc 123 against the driven disc 120 and the driving disc 122 against the driven disc 120.

Thus in response to the operation of the electric motor in turning the shaft 26 the driving discs 122 and 123 are caused to press against the driven disc 120 with pressure sufficient to insure a driving engagement between the electric motor and the engine for engine starting purposes. Hence the electric motor is drivingly connected with the engine and will start the latter. This driving engagement has been effected noiselessly due to

the fact that means independent of the motor have been employed for moving the driving discs against the driven disc before the motor is connected with the current source. Then when the motor is caused to operate it produces noiselessly a pressure between the driving and driven discs sufficient for engine starting purposes.

When the engine becomes self operative and attains a speed such that the linear speed of the driven disc 120 as effected by the engine exceeds the linear speed of the driving discs 122 and 123 as effected by the starting motor, driving engagement between the driving and driven discs of the starter drive is automatically released. This is accomplished due to the fact that as the driven disc 120 tends to run ahead of the driving discs 122 and 123, the rollers 38 tend to run downwardly along the cam surfaces 61 as viewed in Fig. 11, for example. After the engine starts the electromagnet is automatically de-energized by the opening of the automatic switch 110. The suction produced in the engine intake when operating will be sufficient to raise the diaphragm 113 against the action of the spring 115, thereby separating contact 114 from contacts 106 and 107. The spring 91 will then be released to effect movement of the parts 85, 82, 84 and 70 toward the right as viewed in Fig. 3. The spring 76 will also be released so as to move the upper end of the lever 70 toward the right returning it to its normal position as shown in Fig. 1. In this way the engine starter drive parts are restored to normal position as shown in Figs. 1, 2, 4 and 9.

While the electromagnet is energized and the spring 76 is being held in a state of compression greater than normal, the rollers 38 are being urged by yielding pressure afforded by the spring 76 in such direction as to cause the driving discs 122 and 123 to engage with driven discs 120 with yielding pressure. This is desirable first for the purpose of compensating for wear of the friction surfaces of the driving and driven discs. There is another purpose which is important. If the engine should make a weak or false start and fail to attain a speed sufficient to insure self operation, the spring 76 being then held under the pressure greater than normal by the electromagnet, the roller 79 at the lower ends of the arms of lever 70 will press yielding toward the left upon the collar flange 54, thereby causing the threads 52X at collar flange 52 to press yielding upon the helical threads 51 of sleeve 50. Actuating force is thereby stored in the spring 76 which tends to maintain a cooperative relation between the rollers 38 and the cam surfaces 61 so that, if there is any tendency to relieve pressure between the driving and driven discs during a false or weak start of the engine, the rollers 38 will be urged almost instantaneously into a cooperative relation with the cam surfaces 61 so that due to the operation of the motor the wedging action between the driving and driven discs will be repeated. In other words, the spring 76 forms a function analogous to that performed in the conventional one way or overrunning clutch by the springs which are provided each for urging a clutch roller into wedging engagement between the clutch cam and the clutch shell. Thus when the engine attempts to start on its own power and tends to release the driving engagement between the driving and driven discs and then fails to attain a speed sufficient to maintain self operation, the starting motor drive is at all times ready to back up the load of cranking the engine instantaneously.

The electromagnetic means which operates independent of the motor to cause the driving discs to be pressed against the driven disc before the motor is operated is not only a convenient means for preconditioning the starter drive but is one which is well adapted to cooperate with the starter drive of this type. It requires a relatively small force to move the driving disc 123 from its position shown in Fig. 9 to that shown in Fig. 10 where it engages the driven disc 120 and it requires a substantially greater force to move the driving disc 122 into engagement with the driven disc 120 and to effect compression of spring 76 beyond its normal state of compression. The electromagnetic device is well adapted to provide the actuating forces which are required. At first the attraction upon the solenoid armature 82 is relatively small but the force required to move the driving disc 123 toward the right is relatively small. As the solenoid armature 82 approaches the core 83 the attraction increases greatly to give the necessarily greater force required to move the driving disc 122 against the driven disc 120 and to compress the spring 76 beyond its initial state. It is also necessary that the starter switch contact 95 be pressed against the stationary contacts 96 and 97 with a pressure sufficient to insure a good electrical contact. The electromagnet is also well adapted to give this final pressure which is needed between the starter contacts in the starter switch. During final movement of the solenoid armature 82 toward the left when the air gap between the armature and core is closing up the pull upon the armature increases tremendously and is sufficient not only to effect the desired movements of the engine starter drive but also to compress the spring 87 beyond its initial state of compression and to force movable contact 95 firmly against the stationary contacts 96 and 97.

The electromagnet is so constructed as to effect a pull on the armature 82 sufficient to make good electrical contact between the contacts in the starter switch. The magnetic pull required for closing the switch properly is greater than that sufficient for preconditioning the engine starter drive prior to actual operation of the motor. As undue pressure between the driving discs and the driven disc prior to operation of the motor is as undesirable as insufficient pressure the spring 76 operates while the motor switch is closed to limit the force which can be applied by the electromagnet to the shifting lever 70. The spring 76 is so designed that upon being deflected a certain distance by the armature 82 when closing the motor switch the spring will exert the proper force upon the lever 70 tending to rotate it clockwise about its pivotal connection with the link 84. In this way the spring 76 operates not only as a spring exerting yielding pressure upon the shifting collar flange 54 for the purposes herein specified but spring 76 operates also as a means for limiting the amount of pressure which can be effected by the electromagnet.

While the embodiment of the present invention as herein disclosed, constitutes a preferred form, it is to be understood that other forms might be adopted, all coming within the scope of the claims which follow.

What is claimed is as follows:

1. In an engine starter, the combination of a driven disc connected with the engine, a motor, a pair of driving discs driven by the motor and engageable with opposite faces of the driven disc, means independent of the motor for caus-

ing the driving discs to engage the driven disc, and means responsive to the operation of the motor for causing the driving discs to be pressed against the driven disc with a pressure sufficient for driving engagement, said pressure being relieved when the engine becomes self operative.

2. In an engine starter, the combination of a driven disc connected with the engine, a motor, a shaft driven by the motor and having its axis parallel to the axis of the driven disc, a pair of driving discs mounted on the shaft to be driven thereby and slidably thereon, means independent of the motor for causing the driving discs to engage the driven disc, and means responsive to the operation of the motor for causing the driving discs to be pressed against the driven disc with a pressure sufficient for driving engagement, said pressure being relieved when the engine becomes self operative.

3. In an engine starter, the combination of a driven disc connected with the engine, a motor, a shaft driven by the motor and having its axis parallel to the axis of the driven disc, a pair of driving discs mounted on the shaft to be driven thereby and slidably thereon, one of said driving discs being splined to the shaft, means independent of the motor for causing the other driving disc to rotate relative to the shaft, and a cam-and-follower means interconnecting the driving discs so constructed and arranged that rotation of said other driving disc by said independent means causes both driving discs to engage the driven disc prior to motor operation, and motor operation causes the driving discs to be pressed against the driven disc with pressure sufficient for driving engagement.

4. In an engine starter, the combination of a driven disc connected with the engine, a motor, a shaft driven by the motor and having its axis parallel to the axis of the driven disc, a pair of driving discs mounted on the shaft to be driven thereby and slidably thereon, a sleeve carrying one driving disc and splined to the shaft, a spring urging said sleeve in a direction such as to maintain said driving disc normally out of engagement with the driven disc, a second sleeve mounted on the first sleeve and carrying the other driving disc, a cam-and-follower connection between said sleeves such that rotation of the second sleeve relative to the first sleeve causes both driving discs to engage the driven disc and such that rotation of the shaft by the motor causes the driving discs to be pressed against the driven disc with pressure sufficient for driving engagement, and means independent of the motor for causing the first sleeve to rotate.

5. In an engine starter, the combination of a driven disc connected with the engine, a motor, a shaft driven by the motor and having its axis parallel to the axis of the driven disc, a pair of driving discs mounted on the shaft to be driven thereby and slidably thereon, a sleeve carrying one driving disc and splined to the shaft, a spring urging said sleeve in a direction such as to maintain said driving disc normally out of engagement with the driven disc, a second sleeve mounted on the first sleeve and carrying the other driving disc, a cam-and-follower connection between said sleeves such that rotation of the second sleeve relative to the first sleeve causes both driving discs to engage the driven disc and such that rotation of the shaft by the

motor causes the driving discs to be pressed against the driven disc with pressure sufficient for driving engagement, a collar surrounding the second sleeve, a spring surrounding the second sleeve and positioned between the collar and second sleeve, a connection between said collar and second sleeve such that axial movement of the collar effects rotation of the second sleeve, and means for moving the collar axially.

6. In an engine starter, the combination of a driven disc connected with the engine, a motor, a pair of driving discs driven by the motor and engageable with opposite faces of the driven disc, means independent of the motor and including yielding motion transmitting provisions for causing the driving discs to engage the driven disc, and means responsive to the operation of the motor for causing the driving discs to be pressed against the driven disc with a pressure sufficient for driving engagement, said pressure being relieved when the engine becomes self operative.

7. In an engine starter, the combination of a driven disc connected with the engine, a motor, a shaft driven by the motor and having its axis parallel to the axis of the driven disc, a pair of driving discs mounted on the shaft to be driven thereby and slideable thereon, means independent of the motor and including yielding motion transmitting provisions for causing the driving discs to engage the driven disc, and means responsive to the operation of the motor for causing the driving discs to be pressed against the driven disc with a pressure sufficient for driving engagement, said pressure being relieved when the engine becomes self operative.

8. In an engine starter, the combination of a driven disc connected with the engine, a motor, a shaft driven by the motor and having its axis parallel to the axis of the driven disc, a pair of driving discs mounted on the shaft to be driven thereby and slideable thereon, one of said driving discs being splined to the shaft, means independent of the motor and including yielding motion transmitting provisions for causing the other driving disc to rotate relative to the shaft, and a cam-and-follower means interconnecting the driving discs so constructed and arranged that rotation of said other driving disc by said independent means causes both driving discs to engage the driven disc prior to motor operation, and motor operation causes the driving discs to be pressed against the driven disc with pressure sufficient for driving engagement.

9. In an engine starter, the combination of a driven disc connected with the engine, a motor, a shaft driven by the motor and having its axis parallel to the axis of the driven disc, a pair of driving discs mounted on the shaft to be driven thereby and slideable thereon, a sleeve carrying one driving disc and splined to the shaft, a spring urging said sleeve in a direction such as to maintain said driving disc normally out of engagement with the driven disc, a second sleeve mounted on the first sleeve and carrying the other driving disc, a cam-and-follower connection between said sleeves such that rotation of the second sleeve relative to the first sleeve causes both driving discs to engage the driven disc and such that rotation of the shaft by the motor causes the driving discs to be pressed against the driven disc with pressure sufficient for driving engagement, and means independent of the motor and including yielding motion transmitting provisions for causing the first sleeve to rotate.

10. In an engine starter, the combination of a driven disc connected with the engine, a motor, a shaft driven by the motor and having its axis parallel to the axis of the driven disc, a pair of driving discs mounted on the shaft to be driven thereby and slideable thereon, a sleeve carrying one driving disc and splined to the shaft, a spring urging said sleeve in a direction such as to maintain said driving disc normally out of engagement with the driven disc, a second sleeve mounted on the first sleeve and carrying the other driving disc, a cam-and-follower connection between said sleeves such that rotation of the second sleeve relative to the first sleeve causes both driving discs to engage the driven disc and such that rotation of the shaft by the motor causes the driving discs to be pressed against the driven disc with pressure sufficient for driving engagement, a collar surrounding the second sleeve, a spring surrounding the second sleeve and positioned between the collar and second sleeve, a connection between said collar and second sleeve such that axial movement of the second sleeve, and means including yielding motion transmitting provisions for moving the collar axially.

11. In an engine starter, the combination of a driven disc connected with the engine, a motor, a pair of driving discs driven by the motor and engageable with opposite faces of the driven disc, means independent of the motor for causing the driving discs to engage the driven disc, means responsive to the operation of the motor for causing the driving discs to be pressed against the driven disc with a pressure sufficient for driving engagement, said pressure being relieved when the engine becomes self operative, and means responsive to self actuation of the engine for rendering inoperative said means which operates independently of the motor.

12. In an engine starter, the combination of a driven disc connected with the engine, a motor, a shaft driven by the motor and having its axis parallel to the axis of the driven disc, a pair of driving discs mounted on the shaft to be driven thereby and slideable thereon, means independent of the motor for causing the driving discs to engage the driven disc, means responsive to the operation of the motor for causing the driving discs to be pressed against the driven disc with a pressure sufficient for driving engagement, said pressure being relieved when the engine becomes self operative, and means responsive to self actuation of the engine for rendering inoperative said means which operates independently of the motor.

13. In an engine starter, the combination of a driven disc connected with the engine, a motor, a shaft driven by the motor and having its axis parallel to the axis of the driven disc, a pair of driving discs mounted on the shaft to be driven thereby and slideable thereon, one of said driving discs being splined to the shaft, means independent of the motor for causing the other driving disc to rotate relative to the shaft, a cam-and-follower means interconnecting the driving discs so constructed and arranged that rotation of said other driving disc by said independent means causes both driving discs to engage the driven disc prior to motor operation, and motor operation causes the driving discs to be pressed against the driven disc with pressure sufficient for driving engagement, and means responsive to self actuation of the engine for rendering inoperative said means which operates independently of the motor.

14. In an engine starter, the combination of a driven disc connected with the engine, a motor, a shaft driven by the motor and having its axis parallel to the axis of the driven disc, a pair of driving discs mounted on the shaft to be driven thereby and slidably thereon, a sleeve carrying one driving disc and splined to the shaft, a spring urging said sleeve in a direction such as to maintain said driving disc normally out of engagement with the driven disc, a second sleeve mounted on the first sleeve and carrying the other driving disc, a cam-and-follower connection between said sleeves such that rotation of the second sleeve relative to the first sleeve causes both driving discs to engage the driven disc and such that rotation of the shaft by the motor causes the driving discs to be pressed against the driven disc with pressure sufficient for driving engagement, means independent of the motor for causing the first sleeve to rotate, and means responsive to self actuation of the engine for rendering inoperative said means which operates independently of the motor.

15. In an engine starter, the combination of a driven disc connected with the engine, a motor, a shaft driven by the motor and having its axis parallel to the axis of the driven disc, a pair of driving discs mounted on the shaft to be driven thereby and slidably thereon, a sleeve carrying one driving disc and splined to the shaft, a spring urging said sleeve in a direction such as to maintain said driving disc normally out of engagement with the driven disc, a second sleeve mounted on the first sleeve and carrying the other driving disc, a cam-and-follower connection between said sleeves such that rotation of the second sleeve relative to the first sleeve causes both driving discs to engage the driven disc and such that rotation of the shaft by the motor causes the driving discs to be pressed against the driven disc with pressure sufficient for driving engagement, a collar surrounding the second sleeve, a spring surrounding the second sleeve and positioned between the collar and second sleeve, a connection between said collar and second sleeve such that axial movement of the collar effects rotation of the second sleeve, means for moving the collar axially, and means responsive to self actuation of the engine for rendering the collar moving means inoperative.

16. In an engine starter drive, two axially movable driving discs adapted to engage opposite sides of a driven disc connected with the engine, means for positively connecting one of the driving discs with a starting motor, and means interconnecting the two discs so constructed and arranged that rotation in a certain direction of the disc not positively connected with the starting motor relative to the other disc causes both driving discs to engage the driven disc and that the tendency of the driving disc positively connected with the motor to rotate, when driven by the motor, ahead of the other driving disc will cause both driving discs to be urged against said driven disc with pressure sufficient for engine starting purposes, and that this pressure will be relieved when the engine starts, and means for effecting rotation of the disc not positively connected with the motor in said certain direction relative to the other driving disc.

17. In an engine starter drive, two axially movable driving discs adapted to engage opposite sides of a driven disc connected with the engine, a sleeve splinedly connected with the shaft of a

starting motor and carrying one of the driving discs, a second sleeve rotatable and slidable upon the first sleeve and carrying the other driving disc, and means interconnecting the two sleeves so constructed and arranged that rotation in a certain direction of the second sleeve relative to the first sleeve causes both driving discs to engage the driven disc and that the tendency of the first sleeve to rotate, when driven by the motor, ahead of the second sleeve will cause both driving discs to be urged against said driven disc with pressure sufficient for engine starting purposes, and that this pressure will be relieved when the engine starts, and means for effecting rotation of the second sleeve in said certain direction relative to the first sleeve.

18. A starter drive for an internal combustion engine and adapted to be operated by a starting motor, comprising a pair of driving discs adapted to be driven by a starting motor and engageable with a driven disc connected to the engine shaft, means other than the motor to move the driving discs into position to engage the driven disc, and means operable in response to operation of the starting motor for forcing the driving discs against the driven disc with a pressure sufficient to drive the engine, said means being constructed so as to relieve the pressure of the driving discs on the driven disc when the engine becomes self-operative.

19. A starter drive for internal combustion engines adapted to be associated with a starting motor having a driving shaft and comprising, a pair of driving discs adapted to be driven by the starting motor and engageable with a driven disc connected to the engine shaft, said driving discs being slidably supported by the driving shaft of the starting motor, and being adapted to be moved into engagement with the driven disc by means operable independently of the starting motor, means operable in response to the operation of the starting motor for forcing the driving discs against the driven disc with a pressure sufficient to drive the engine, said means being constructed so as to relieve the pressure of the driving discs on the driven disc when the engine becomes self-operative.

20. A starter drive for internal combustion engines adapted to be associated with a starting motor having a driving shaft and comprising, a pair of driving discs adapted to be driven by the starting motor and engageable with a driven disc connected to the engine shaft, said driving discs being slidably supported by the driving shaft of the starting motor, and one of said discs being splined to the shaft, means independent of the motor for causing the other driving disc to rotate relative to the shaft and cam and follower means interconnecting the driving discs so constructed and arranged that rotation of said other driving disc by said independent means causes both driving discs to engage the driven disc prior to operation of the starting motor, and motor operation causes the driving discs to be pressed against the driven disc with pressure sufficient to drive the engine shaft.

21. A starter drive for internal combustion engines adapted to be associated with a starting motor having a driving shaft and comprising, a pair of driving discs adapted to be driven by the starting motor and engageable with a driven disc connected to the engine shaft, said driving discs being slidably supported by the driving shaft of the starting motor, and one of said discs being

splined to the shaft, means independent of the motor for causing the other driving disc to rotate relative to the shaft, cam and follower means interconnecting the driving discs so constructed and arranged that rotation of said other driving disc by said independent means causes both driving discs to engage the driven disc prior to operation of the starting motor, and motor operation causes the driving discs to be pressed against the driven disc with pressure sufficient to drive the engine shaft, said means being construed so as to release the driving discs from the driven disc when the engine runs under its own power.

22. A starter drive for internal combustion engines adapted to be associated with a starting motor having a driving shaft and comprising, a pair of driving discs adapted to be driven by the starting motor and engageable with a driven disc connected to the engine shaft, said driving discs being slidably supported by the driving shaft of the starting motor, a sleeve carrying one driving disc and splined to the shaft, a spring urging said sleeve in a direction such as to maintain said driving disc normally out of engagement with the driven disc, a second sleeve mounted on the first sleeve and carrying another driving disc, a cam and follower connection between said sleeves such that rotation of the second sleeve relative to the first sleeve causes both driving discs to engage the driven disc and such that rotation of the shaft by the motor causes the driving discs to be pressed against the driven disc with pressure sufficient for driving engagement and means independent of the starting motor for causing the first sleeve to rotate.

23. A starter drive for internal combustion engines adapted to be associated with a starting motor having a driving shaft and comprising, a pair of driving discs adapted to be driven by the starting motor and engageable with a driven disc connected to the engine shaft, said driving discs being slidably supported by the driving shaft of the starting motor, and engageable with opposite faces of the driven disc, means independent of the motor and including yielding motion transmitting provisions for causing the driving discs to engage the driven disc and means responsive to the operation of the motor for causing the driving discs to be pressed against the driven disc with a pressure sufficient for driving engagement.

24. A starter drive for internal combustion engines adapted to be associated with a starting motor having a driving shaft and comprising, a pair of driving discs adapted to be driven by the starting motor and engageable with a driven disc connected to the engine shaft, said driving discs being slidably supported by the driving shaft of the starting motor, and engageable with opposite faces of the driven disc, means independent of the motor and including yielding motion transmitting provisions for causing the driving discs to engage the driven disc, means responsive to the operation of the motor for causing the driving discs to be pressed against the driven disc with a pressure sufficient for driving engagement, and means whereby said pressure is relieved when the engine becomes self-operative.

25. A starter drive for internal combustion engines adapted to be associated with a starting motor having a driving shaft and comprising, a pair of driving discs adapted to be driven by the starting motor and engageable with a driven disc connected to the engine shaft, said driving discs being slidably supported by the driving shaft of the starting motor, and one of said discs being splined

to the shaft, means independent of the motor and including yielding motion transmitting connections for causing the other driving disc to rotate relative to the shaft, and cam and follower means 5 interconnecting the driving discs so constructed and arranged that rotation of said other driving disc by said independent means causes both driving discs to engage the driven disc prior to motor operation, and motor operation causes the driving 10 discs to be pressed against the driven disc with pressure sufficient for driving engagement.

pressure sufficient for driving engagement.

26. An engine starter drive for internal combustion engines adapted to be associated with a starting motor having a driving shaft and comprising, a pair of driving discs adapted to be mounted on the motor shaft and to cooperate with a driven disc having an axis parallel to the axis of the motor shaft, said driving discs being slidable on the motor shaft, a sleeve carrying one disc and adapted to be splined to the shaft, a spring urging said sleeve in a direction such as to maintain said driving disc normally out of engagement with the driven disc, a second sleeve mounted on the first sleeve and carrying the other driving disc, a cam and follower connection between said sleeves such that rotation of the second sleeve relative to the first sleeve causes both driving discs to engage the driven disc and such that rotation of the shaft by the motor causes the driving discs to be pressed against the driven disc with pressure sufficient for driving engagement, and means independent of the motor and including yielding motion transmitting provisions for causing the first sleeve to rotate.

35   27. An engine starter drive for internal combustion engines adapted to be associated with a starting motor having a driving shaft and comprising, a pair of driving discs adapted to be mounted on the motor shaft and to cooperate with a driven disc having an axis parallel to the axis of the motor shaft, said driving discs being 40 slideable on the motor shaft, a sleeve carrying one disc and adapted to be splined to the shaft, a spring urging said sleeve in a direction such as to maintain said driving disc normally out of engagement with the driven disc, a second sleeve mounted on the first sleeve and carrying the other driving disc, a cam and follower connection between said sleeves such that rotation of the 45 second sleeve relative to the first sleeve causes both driving discs to engage the driven disc and such that rotation of the shaft by the motor causes the driving discs to be pressed against the driven disc with pressure sufficient for driving engagement, a collar surrounding the second sleeve, a 50 connection between said collar and second sleeve, a spring surrounding said second sleeve and positioned between the collar and the sleeve, a connection between said collar and second sleeve 55 such that axial movement of the collar effects rotation of the second sleeve and means including yielding motion transmitting provisions for moving the collar axially.

23. A starter drive for internal combustion engines adapted to be associated with a starting motor having a driving shaft and comprising, two axially movable driving discs adapted to engage opposite sides of a driven disc connected with the engine shaft, means adapted to positively connect one of said driving discs with the motor shaft, and means interconnecting the two discs so constructed and arranged that rotation in a certain direction of the disc not positively connected with the motor shaft relative to the other disc causes both driving discs to engage

the driven disc and that the tendency of the positively connected driving disc to rotate ahead of the other driving disc, when driven by the motor, will cause both driving discs to be urged against the driven disc with pressure sufficient for engine starting purposes and that this pressure will be relieved when the engine starts, and means for effecting rotation of the disc which is not adapted to be positively connected to the motor shaft in said certain direction relative to the other driving disc.

29. A starter drive for internal combustion engines adapted to be associated with a starting motor having a driving shaft and comprising, two axially movable driving discs adapted to engage opposite sides of a driven disc connected with the engine shaft, a sleeve supporting one of the discs and adapted to be splined to the motor shaft, a second sleeve rotatable and slidable on the first sleeve and carrying the other driving disc, and means interconnecting the two sleeves so constructed and arranged that rotation in a certain direction of the second sleeve relative to the first sleeve causes both driving discs to engage the driven disc and that the tendency of the first sleeve to rotate ahead of the second sleeve, when driven by the motor, will cause both driving discs to be urged against the driven disc with sufficient pressure for engine starting purposes and that this pressure will be relieved when the engine starts, and means for effecting rotation of the second sleeve in said certain direction relative to the first sleeve.

30. For use in an engine starting apparatus having a starting motor adapted to operate the engine to be started, a starter drive through which the starting motor operates the engine and having, in combination, two axially movable driving discs adapted to engage opposite sides of a driven

disc connected with the engine, means for positively connecting one of the driving discs with the starting motor, and means interconnecting the two driving discs so constructed and arranged 5 that the tendency of the driving disc positively connected with the motor to rotate, when driven by the motor, ahead of the other driving disc will cause both driving discs to be urged against said driven disc with pressure sufficient for engine starting purposes, and that this pressure will be relieved when the engine starts, said starter drive having means adapted to be acted upon by a force other than that of the starting motor to effect an initial movement of the driving discs 10 for engagement with the driven disc.

31. For use in an engine starting apparatus having a starting motor adapted to operate the engine to be started, a starter drive through which the starting motor operates the engine and having, in combination, two axially movable driving discs adapted to engage opposite sides of a driven disc connected with the engine, a sleeve splinedly connected with the shaft of the starting motor and carrying one of the driving discs, a second sleeve rotatable and slidable upon the first sleeve and carrying the other driving disc, and means interconnecting the two sleeves so constructed and arranged that the tendency of the first sleeve to rotate, when driven by the motor, ahead of the second sleeve will cause both driving discs to be urged against said driven disc with pressure sufficient for engine starting purposes, and that this pressure will be relieved when the engine starts, said starter drive having means adapted to be acted upon by a force other than that of the starting motor to effect an initial movement of the driving discs for engagement with the driven disc.

JOHN B. DYER.
